PROCESS FOR TREATING PETROLEUM EMULSIONS

Raymond W. Todd and Fritz E. Fuchs, Houston, Tex., assignors to Aquaness Corporation, Houston, Tex., a corporation of Texas

No Drawing. Application March 19, 1951,
Serial No. 216,474

11 Claims. (Cl. 252—342)

1

This invention relates to the treatment of emulsions of mineral oil and water, particularly water-in-oil petroleum emulsions, for the purpose of separating the oil from the water.

An object of this invention is to provide an improved process for breaking or separating petroleum emulsions by subjecting such emulsions to the action of a novel demulsifying composition to be described in greater detail hereinafter.

Another object is the provision of a novel demulsifier composition which is highly effective for breaking or separating petroleum emulsions.

The new demulsifier in accordance with this invention comprises a class of esterification products obtained by the reaction of a fatty acid with a particular type of hydroxylated compound.

The hydroxylated compounds employed as the intermediates in forming the final esterification product are of a specific character obtained by the reaction of an alkyl polyhydroxy compound initially containing three or more free hydroxyl groups with an oxyalkylating material consisting essentially of mixtures of ethylene oxide and propylene oxide in particular proportions.

The alkyl polyhydroxy compounds which are particularly adapted for preparation of the intermediate materials employed in making the final demulsifier composition are best exemplified by the class consisting of glycerol, polyglycerol, pentaerythritol, sorbitol, mannitol and the like. Polyglycerol is a polymer of glycerol, having in its simplest form, four free hydroxyl groups and a single ether linkage connecting two glycerol residues as may be illustrated by the following formula:

The specific oxyalkylating compounds comprise mixtures of ethylene oxide and propylene oxide in which the propylene oxide constitutes from about 15% to about 60% by weight of the mixture. In most cases a 50-50 mixture by weight of these oxides is found to be preferable. The quantity of the mixed oxides used and their relative proportions in the mixtures will ordinarily be such as to produce an oxyalkylated polyhydroxy compound having an average molecular weight of from about 2500 to 7500, and preferably about 5000. The resulting oxyalkylated compounds are all clear, relatively low-viscosity liquids completely soluble in water in all proportions.

2

The fatty acids employed in making the final ester product may be any of the well known long chain, soap-forming fatty acids having 8 to 18 carbon atoms in the chain, such as stearic, oleic, ricinoleic, soya bean fatty acids, tall oil, linseed oil fatty acids, cocoa-nut fatty acids, and the like. The molal proportion of fatty acid to the oxyalkylated intermediate compounds may be varied to form either partial esters or fully esterified compounds or mixtures thereof. The mono-, di- or tri-ester compounds appear generally to be the more effective compounds. The final ester compounds are all clear, moderately viscous liquids which are completely soluble or miscible with water in all proportions.

The procedure for oxyalkylating the polyhydroxy compounds is generally in accordance with well known procedures except that in every case the ethylene and propylene oxides are intermixed and reacted in mixed condition with the polyhydroxy material.

The resulting oxyalkylated polyhydroxy intermediates are then reacted in appropriate proportions with the selected fatty acid to produce the desired ester products. This esterifying reaction is conducted in accordance with well known procedures for effecting esterification between a hydroxy compound and an acid.

Following are several examples of the method of manufacture of the oxyalkylated polyhydroxy intermediate compounds and the final ester compounds employed in the process in accordance with the present invention:

OXYALKYLATED POLYHYDROXY INTERMEDIATE

Example 1

46 pounds ($\frac{1}{2}$ mol) of glycerol, to which may be added about 4 pounds of sodium methylate as a catalyst, are placed in a water-jacketed pressure chamber and heated to about 250° F. The chamber is purged with natural gas or methane and an atmosphere of such gas at a pressure of about 50 pounds per square inch is maintained in the chamber. 1250 pounds of ethylene oxide and 1250 pounds of propylene oxide are then pumped into the chamber, the oxides being intermixed as they are fed into the chamber. The oxides react with the glycerol and the resulting reaction tends to raise the temperature and pressure sharply. External heating is cut off and by circulation of cooling water the temperature is maintained within a range of from about 270 to about 350° F. The pressure is held to a range of from about 80 to 125 pounds per

square inch. As the reaction proceeds and the oxides are used up, the pressure drops to about that of the blanketing gas, about 50 pounds per square inch, when the reaction is completed. About 3 to 4 hours is required to complete the reaction.

The proportions of materials used in this example will produce an oxyalkylated product having an average molecular weight of about 5000 and this product is a light colored, relatively low-viscosity liquid which is completely soluble in cold water.

Example 2

About 1875 pounds each of ethylene and propylene oxides are used instead of 1250 pounds each as in Example 1, and will produce an oxyalkylated glycerol product having a molecular weight of about 7500.

Example 3

About 625 pounds each of ethylene and propylene oxides are used instead of the amounts stated in the previous examples to produce an oxyalkylated product having a molecular weight of about 2500.

Example 4

83 pounds of polyglycerol are substituted for the 46 pounds of glycerol in each of Examples 1, 2 and 3, above.

FINAL ESTER PRODUCT

Example 1

5000 pounds (1 mol) of the Oxyalkylated Polyhydroxy Intermediate, Example 1 above, is mixed with 282 pounds (1 mol) of oleic acid in the presence of a small amount of sulfuric acid catalyst and heated at 140-150° F. for from about 8 to 10 hours to produce the mono-ester. The latter is a clear, dark amber, relatively low-viscosity liquid which is completely soluble in water in all proportions.

Example 2

7500 pounds and 2500 pounds, respectively, of the Oxyalkylated Polyhydroxy Intermediates, Example 1 and Example 2, are substituted for the 5000 pounds of Oxyalkylated Polyhydroxy Intermediate, Example 1 in Final Ester Product, Example 1 above, to produce the corresponding mono-esters.

Example 3

564 pounds (2 mols) of oleic acid is substituted for the 282 pounds in Final Ester Products, Examples 1 and 2, above, to produce the corresponding di-esters.

Example 4

350 pounds of tall oil are used in place of the 282 pounds of oleic acid in each of the Final Ester Products, Examples 1 and 2 above, to produce the corresponding tall oil esters.

Example 5

700 pounds of tall oil are substituted in each case for the 564 pounds of oleic acid in Example 3 above.

Example 6

Molecular equivalents of cocoanut fatty acids, soya bean fatty acids, stearic acid, or ricinoleic acid may be substituted for the oleic acid and tall oil in each of the Final Ester Products, Examples 1, 2, 3, 4 and 5 above.

From the foregoing it will be understood that the demulsifier compositions employed in accordance with the present invention are fatty acid esters of a specific class of oxyalkylated polyhydroxy compounds, namely, aliphatic polyhydroxy compounds initially having three or more free hydroxyl groups which have been oxyalkylated with mixtures of ethylene and propylene oxides in the relative proportions stated above to produce compounds within the particular ranges of molecular weight above specified.

This specific group of compounds have been found to be exceptionally effective for breaking water-in-oil petroleum emulsions.

These compounds may be used directly but preferably are diluted by suitable thinners, such as water, alcohol, aromatic solvents and the like. They may also be used in mixture with other well known petroleum demulsifying agents, if desired.

In practicing the process, a treating agent or demulsifying agent of the kind above described may be brought in contact with the emulsion to be treated in any of the numerous ways now employed in the treatment of petroleum emulsions with chemical demulsifying agents, such, for example, as by introducing the treating agent into the well in which the emulsion is produced, introducing the treating agent into a conduit through which the emulsion is flowing, introducing the treating agent into a tank in which the emulsion is stored, or introducing the treating agent into a container that holds a sludge obtained from the bottom of an oil storage tank. In some instances, it may be advisable to introduce the treating agent into a producing well in such a way that it will become mixed with water and oil that are emerging from the surrounding strata, before said water and oil enter the barrel of the well pump or the tubing up through which said water and oil flow to the surface of the ground. After treatment the emulsion is allowed to stand in a quiescent state, usually in a settling tank, at a temperature varying from atmospheric temperature to about 200° F., so as to permit the water or brine to separate from the oil, it being preferable to keep the temperature low enough so as to prevent the valuable constituents of the oil from volatilizing. If desired, the treated emulsion may be acted upon by one or the other of various kinds of apparatus now used in the operation of breaking petroleum emulsions, such as homogenizers, hay tanks, gun barrels, filters, centrifuges, or electrical dehydrators.

The amount of treating agent on the anhydrous basis that is required to break the emulsion may vary from approximately 1 part of treating agent to 500 parts of emulsion, up to a ratio of 1 part of treating agent to 20,000 parts of emulsion, depending upon the type or kind of emulsion being treated. In treating exceptionally refractory emulsions of the kind commonly referred to as "tank bottoms" or "residual pit oils," the minimum ratio above referred to is often necessary, but in treating fresh emulsions, i. e., emulsions that will yield readily to the action of chemical demulsifying agents, the maximum ratio above mentioned will frequently produce highly satisfactory results. For the average petroleum emulsion of the water-in-oil type a ratio of 1 part of treating agent to 10,000 parts of emulsion will usually be found to produce commercially satisfactory results.

What we claim and desire to secure by Letters Patent is:

1. A process for breaking petroleum emulsions

of the water-in-oil type, which consists in subjecting the emulsion to the action of a demulsifying agent consisting essentially of the fatty acid esters of an oxyalkylated polyhydroxy compound derived by the reaction of an alkyl polyhydroxy compound initially having three or more free hydroxyl groups with a mixture of ethylene and propylene oxides in which the proportion of propylene oxide is in the range of from about 15% to about 60% by weight of the mixture, and wherein the proportions of the mixed oxides to the alkyl polyhydroxy compound are such as to produce said oxyalkylated polyhydroxy compound having an average molecular weight ranging from about 2500 to about 7500, and wherein the fatty acid employed in forming said esters is a long-chain detergent forming fatty acid having 8 to 18 carbon atoms in the chain.

2. A process according to claim 1, wherein said esters are formed by reacting at least one mol of the fatty acid to each mol of said oxyalkylated polyhydroxy compound. 20

3. A process according to claim 1 wherein said alkyl polyhydroxy compound is a member of the class consisting of glycerol and polyglycerol. 25

4. A process according to claim 1 wherein said fatty acid is oleic acid.

5. A process according to claim 1 wherein said fatty acid is tall oil. 30

6. A process according to claim 1 wherein said fatty acid is cocoanut oil fatty acid.

7. A process according to claim 1 wherein said fatty acid is soya bean fatty acid. 35

8. A process according to claim 1 wherein said fatty acid is stearic acid.

9. A process for breaking petroleum emulsions of the water-in-oil type, which consists in subjecting the emulsion to the action of a demulsifying agent consisting essentially of the oleic acid esters of oxyalkylated glycerol derived by reacting glycerol with a mixture of ethylene and propylene oxides in equal proportions by weight, and in an amount sufficient to produce an oxyalkylated glycerol having a molecular weight of about 5000. 10

10. A process according to claim 9 wherein the oleic acid esters are formed by reacting at least one mol of oleic acid to each mol of said oxyalkylated glycerol.

11. A process according to claim 9 wherein the oleic acid esters are formed by reacting two mols of oleic acid to each mol of said oxyalkylated glycerol. 15
